Attest:

UNITED STATES PATENT OFFICE

HOWARD E. TRITES, OF BRIDGEWATER, MASSACHUSETTS

POULTRY DRINKING STAND

Application filed February 24, 1930. Serial No. 430,777.

The chief object of this invention is to provide a structure on which fowls may stand to drink, the structure being adapted to collect and segregate droppings from fowls standing thereon, and permit the transference of the collected droppings from time to time to a manure pile, the structure being so organized that it may easily be cleaned and kept in a sanitary condition.

10 Of the accompanying drawings forming a part of this specification,—

Figure 1 is a perspective view of a structure or drinking stand embodying the invention.

15 Figure 2 is a sectional view of the same.

Figures 3, 4 and 5 show in perspective and separated from each other, elements of the structure shown by Figures 1 and 2.

20 Figure 6 is a fragmentary perspective view, showing a portion of the upper member of the base frame.

The same reference characters indicate the same parts in all of the figures.

25 My improved stand includes a base frame which is preferably circular and bounds a space 13.

In this instance, the frame is composed of an annular lower member 12, upstanding from a bottom 14 having supporting means such as legs 15, and an upper member angular in cross section and including an upstanding annular body 16, and an annular flange 17, projecting inward from the body and bearing 30 removably on the upper edge of the member 12. Said flange is provided with stops 18, bearing on the inner side of the member 12 and preventing edgewise or horizontal displacement of the upper member.

Bearing 35 removably on the body 16 of the upper member is a grid adapted to support fowls, and also to support a pan 19, from which fowls standing on the grid may drink. Openings in the grid are adapted to permit the passage through the grid of droppings from the fowls.

The grid is preferably composed of a layer 20 of open mesh wire fabric having square meshes or openings about half an inch wide, these openings permitting droppings to fall through the grid, and reinforcing members

of relatively thick wire, including a circular member 21, soldered or otherwise attached to the margin of the layer 20, and straight members 22, attached at their ends to the member 21, and extending in different directions across the same, the layer 20 bearing on the reinforcing members.

Figure 3 shows the layer 20 separately, as it appears before its attachment to the reinforcing members.

The described grid constitutes a practically unyielding support adapted to bear removably on the base frame, and adequately support the pan 19, and a considerable number of fowls in drinking position.

The pan 19 is so proportioned that when supported by the central portion of the grid, its margin is spaced from the margin of the grid a distance permitting droppings from fowls in drinking position to pass through openings in the grid. The diameter of the grid may be about three feet, and that of the pan about eighteen inches.

Located under the grid is a receptacle for said droppings. Said receptacle preferably includes a circular layer 23 of open mesh wire fabric, and a marginal annular reinforcing member 24 attached to the margin thereof. The meshes or openings in the layer 23 are considerably smaller than those in the grid layer 20, and of such size that droppings cannot fall therethrough.

The layer 23 is preferably dished, as shown by Figure 2, so that it has a raised marginal portion and a depressed portion surrounded by the marginal portion. Droppings are therefore adapted to roll on the layer 23 to the central portion thereof.

The droppings receptacle rests loosely on the flange 17 of the base frame, the grid rests loosely on the body portion 16, and the pan rests loosely on the grid. The parts are therefore adapted to be separately cleaned, and the structure as a whole, kept in a sanitary condition. The segregation by the layer 23 of droppings from fowls standing on the grid, prevents objectionable scattering of the droppings, and enables them to be conveniently deposited on a manure pile. Any water scattered by the fowls while drinking

falls through the grid and through the layer 23, and may escape through an outlet 26, from which it may be conducted by a waste pipe 27, leading to a drain.

5 Excessive sagging of the layer 23 constituting the droppings receptacle, may be prevented by wire reinforcing members 28 (Figure 2) secured to the marginal member 24 and bearing on the under side of the layer 23.

10 The grid preferably has stop means preventing its edgewise displacement on the base frame, said means being provided, in this instance, by the reinforcing member 21, which projects below the member 22 and 15 abuts the upper edge of the base frame, as shown by Figure 2.

I claim:

1. A poultry drinking stand, comprising an open base frame horizontally supported, 20 a fowl-supporting grid bearing removably on the frame and covering the space bounded thereby, said grid having openings for the passage of droppings therethrough, a water receptacle supported by the grid and spaced 25 from the margin thereof a distance permitting droppings from fowls, in drinking position on the grid, to pass through grid openings, and a receptacle for droppings removably supported by the frame under the grid, 30 the grid being composed of a layer of wire fabric of relatively coarse mesh, and reinforcing members including a marginal member attached to the margin of said layer, and transverse members fixed at their ends to 35 the marginal member and extending in different directions across the same.

2. A poultry drinking stand, comprising an open base frame horizontally supported, 40 a fowl-supporting grid bearing removably on the frame and covering the space bounded thereby, said grid having openings for the passage of droppings therethrough, a water receptacle supported by the grid and spaced 45 from the margin thereof a distance permitting droppings from fowls, in drinking position on the grid, to pass through grid openings, and a receptacle for droppings removably supported by the frame under the grid, the droppings receptacle being composed of 50 a layer of wire fabric of relatively fine mesh, and a marginal reinforcing member attached to the margin thereof.

3. A poultry drinking stand, comprising an open base frame horizontally supported, 55 a fowl-supporting grid bearing removably on the frame and covering the space bounded thereby, said grid having openings for the passage of droppings therethrough, a water receptacle supported by the grid and spaced 60 from the margin thereof a distance permitting droppings from fowls, in drinking position on the grid, to pass through grid openings, and a receptacle for droppings removably supported by the frame under the grid, 65 the droppings receptacle being composed of a

layer of wire fabric of relatively fine mesh, and a marginal reinforcing member attached to the margin thereof, said layer being dished to cause droppings deposited on a marginal portion thereof to roll to a common locus.

4. A poultry drinking stand, comprising an open base frame horizontally supported, 70 a fowl-supporting grid bearing removably on the frame and covering the space bounded thereby, said grid having openings for the 75 passage of droppings therethrough, a water receptacle supported by the grid and spaced from the margin thereof a distance permitting droppings from fowls, in drinking position on the grid, to pass through grid openings, and a receptacle for droppings removably supported by the frame under the grid, the base frame being provided with a bottom 80 having a contracted outlet for water falling through the grid and through the droppings 85 receptacle.

5. A poultry drinking stand, comprising an open base frame horizontally supported, a fowl-supporting grid bearing removably on the frame and covering the space bounded 90 thereby, said grid having openings for the passage of droppings therethrough, a water receptacle supported by the grid and spaced from the margin thereof a distance permitting 95 droppings from fowls, in drinking position on the grid, to pass through grid openings, and a receptacle for droppings removably supported by the frame under the grid, the base frame being composed of an annular 100 upstanding lower member having supporting means, and an upper member angular in cross section and including an upstanding annular body and an annular flange projecting inward from the body, and bearing removably on the upper edge of the lower 105 member, said flange having stops engaging the lower member, to prevent edgewise displacement of the upper member, the grid bearing removably on the upper edge of the 110 upper member and the droppings receptacle bearing removably on said flange.

6. A poultry drinking stand, comprising an open base frame horizontally supported, a fowl-supporting grid bearing removably on the frame and covering the space bounded 115 thereby, said grid having openings for the passage of droppings therethrough, a water receptacle supported by the grid and spaced from the margin thereof a distance permitting 120 droppings from fowls, in drinking position on the grid, to pass through grid openings, and a receptacle for droppings removably supported by the frame under the grid, the grid being provided with stop means 125 co-operating with the base frame to prevent edgewise displacement of the grid.

In testimony whereof I have affixed my signature.

HOWARD E. TRITES. 130
